H. W. HEINE

PARTITION WALL

Filed April 10, 1923

INVENTOR
Henry W. Heine.
BY *W. H. Bauer*

ATTORNEY

UNITED STATES PATENT OFFICE.

HENRY W. HEINE, OF WASHINGTON, DISTRICT OF COLUMBIA.

PARTITION WALL.

Application filed April 10, 1923. Serial No. 631,168.

To all whom it may concern:

Be it known that I, HENRY W. HEINE, a citizen of the United States, and a resident of Washington, District of Columbia, have 5 invented certain new and useful Improvements in Partition Walls, of which the following is a specification.

This invention relates to partition walls.

The present invention more particularly 10 relates to partition walls in which channel irons or the like are employed for studding or posts and plaster boards or the like for forming the wall.

The object of the invention is to provide 15 an improved means for securing the plaster boards to the posts or studding with the view of obtaining an exceedingly rigid wall at a relative low cost.

It is also an important object of the invention that the securing means be easily applied and thus to build a wall with a minimum of labor.

Other objects, and objects relating to details of construction, combination and arrangement of parts will hereinafter appear 25 in the detailed description to follow.

The invention is illustrated by way of example in the accompanying drawings, in which:—

30 Figure 1 is a fragmentary perspective view illustrating a partition wall embodying the present invention,

Figure 2 is a group view illustrating the different securing elements for the plaster 35 boards of this invention, and

Figures 3 and 4 are fragmentary horizontal sectional views illustrating the manner in which the securing elements employed serve to grip or clamp the plaster boards 40 for tying the same to the supports.

Referring to the drawings more particularly, 10 indicates generally a channel iron which is employed as a studding or post between the ceiling and floor in the room 45 or building in which a partition is to be constructed. In Figure 1, there is shown a pair of plaster boards 11 which might be of any dimensions desired. The channel iron 10 has its bridge portion 12 provided 50 with a plurality of spaced slots or openings 13 which are arranged adjacent the side 14 of the channel iron. Each opening is adapted to receive a wedge 15, said wedge preferably comprising a plate-like member tapering toward its one end and arcuate longitudinally as illustrated to advantage in

Figure 2 of the drawings. The wedges 15 are preferably of spring metal and may be referred to as yieldable spring elements which, when positioned, extend laterally 60 from each side of the support 10 and thus forming lateral extensions against which wall boards may be positioned.

The channel iron is also provided with a plurality of key receiving openings 16 which are arranged adjacent the side or flange 17 of said channel iron. Each opening 16 is adapted to receive a key 18, which in the present instance, is in the form of a nail including the usual head 20. The distance 70 between a vertical line or plane extended to coincide with the inner edges of slots 13, and a plane or line passing through the openings 16, should be approximately equal to the thickness of the plaster boards 11. 75

It might be here mentioned that the slots 13 together with the holes or openings 16 could be easily made at the time the channel bars are formed, that is, when formed from cold sheet metal. As is well known, these 80 channel irons are made from relatively light or thin sheet metal and therefore no difficulty should arise in punching the holes 16 and slots 13. In assembling the wall the channel members 10 are of course first 85 positioned and then a person may take a number of wedges 15 and position them in the slots 13 of the channel members 10. The wedges for each of the channel members might first be positioned and then the plaster boards placed thereagainst 90

as shown in Figure 3. These nails or keys are extended through the openings 16 and driven to the position illustrated in Figures 1 and 4. The nail heads 20 engage the plaster boards upon one side of the channel iron in such a manner that a wedging action occurs, whereby to straighten the wedges 15 and clamp the ends of the plaster board occurring upon each side of a channel member. Other boards may now be placed 100 in position and as is obvious, one man can readily build a wall in a quick and efficient manner. In substance a durable and strong wall may be assembled or built quickly and 105 with a minimum of labor.

The securing elements, viz., the keys 18, wedges 15 and supports 12 are shown as employed for securing boards 11 in forming a partition. However, I wish it understood 110 I am aware of the fact that these elements could be used for securing structural ele-

ments other than boards, with certain advantages, and also that other forms of supports 12 might be used. Furthermore, the securing elements above mentioned can 5 be employed in a ceiling structure to advantage. In a ceiling structure the wedges referred to would support the ceiling in conjunction with the structural supports employed for the channels 12. Also it might 10 here be noted that the wedges 15 can be made of any desired strength, that is, the strength of the wedges should be dependent upon the strain to which the same would be subjected. If used in a light partition wall 15 then the wedges could be correspondingly light in structure; but if used for a heavy partition wall or the like, or for a ceiling structure then these wedges should be relatively heavy.

20 I claim:—

1. In a building construction, a pair of aligned boards, a supporting member between the opposing ends of the boards, lateral extensions carried by the support, said extensions being resilient and curved toward the associated faces of the boards, and keys driven through openings in the support adapted to engage the opposite faces of the boards and press said boards to engage and 30 straighten the lateral extensions and thus to tie the boards to said support.

2. In a building construction, a pair of aligned boards, a supporting member between the opposing ends of the boards, lateral extensions carried by the support, said exten- 35

sions being resilient and curved toward the associated faces of the boards, and nails driven through openings in the support so that the same will engage the opposite faces of the boards and force the same toward the lateral extensions whereby to straighten said extensions and tie the boards to said supports. 40

3. In a wall construction, wall boards, a supporting member having spaced slots in one side thereof and spaced openings upon the other side, said slots and openings being spaced at a distance substantially equal to the thickness of said wall boards, wedges extending into said slots, said wedges being 45 curved in longitudinal section and with the concave faces thereof opposing said wall boards, and nails driven into said openings and engaging the opposite faces of the wall boards whereby to force the boards for straightening the wedges and thereby tie the boards to said support. 50

4. In a building structure, a pair of aligned boards, a supporting member between the opposing ends of the boards, yieldable spring elements extending from the support against which the boards may be pressed and keys driven through openings in the support whereby to force the boards against said spring elements and thus 60 enable the spring elements and the keys to be tensioned for relative high pressure against the faces of the boards and in this way solidly tie the boards to said support. 65

HENRY W. HEINE.
